UNITED STATES PATENT OFFICE.

WARREN B. HOPKINS, OF BROOKLINE, MASSACHUSETTS.

GREASE CONTAINER AND GUN THEREFOR.

Application filed November 17, 1921. Serial No. 515,949.

To all whom it may concern:

Be it known that I, WARREN B. HOPKINS, a citizen of the United States, residing at Brookline, in the county of Norfolk and State of Massachusetts, have invented new and useful Improvements in Grease Containers and Guns Therefor, of which the following is a specification.

This invention relates to an improved container for grease and to an improved gun in which said container may be positioned and whereby the grease in said container may be ejected from said gun.

The object of the invention is to provide a container for grease which can be sold at a low price and which can be placed in a grease gun or grease cup, the same being particularly adapted for use in greasing the bearings of different parts of an automobile without the user being obliged to soil his hands by inserting the grease in said gun or in said grease cup.

The invention consists in the improved container for grease hereinafter fully described and set forth in the claims, and the invention further consists in the combination of said container with a grease gun or grease cup capable of having the container positioned therein, and also capable of forcing the grease out of said container and out of said grease gun or grease cup.

The invention further consists in the combination and arrangement of parts set forth in the following specification and particularly pointed out in the claims thereof.

Referring to the drawings:

Figure 1 is a side elevation of my improved grease gun with my improved grease container positioned therein.

Fig. 2 is a longitudinal vertical sectional elevation of the same, the plunger in Figs. 1 and 2 being broken away.

Fig. 3 is a detail longitudinal sectional elevation of the grease container.

Fig. 4 is a sectional elevation illustrating my improved grease container positioned in a grease cup.

Like numerals refer to like parts throughout the several views of the drawings.

In the drawings, referring to Figs. 1, 2 and 3, 5 is the grease container and 6 the grease gun. The grease container consists of a tube 7, preferably formed of paper, and having its opposite ends turned inwardly to form flanges 8 and 9. The tube 7 is provided with an end closure 10, preferably

formed of paper, and fast to one end of the tube 7. Said end closure 10 is provided with an orifice 11 in which is located a tapered eyelet 12 and the opposite faces of the eyelet 12 are covered with a frangible material 13 and 14, said frangible material being preferably thin paper. The end closure 10 rests against the flange 8. The opposite end of the tube 7 is closed by an end closure 15 preferably composed of layers of cardboard. This end closure is slidable in the container 7 and when the container is filled with grease, the slidable end closure 15 rests against the flange 9.

The grease gun 6 consists of a tube 16 which is cut out at 17 in order that the container 5 may be introduced into said tube. One end 18 of said grease gun is screwed onto the tube 6 and has an orifice 19 therein which aligns with the orifice in the eyelet 12. Said end 18 also has a conical projection 20 extending inwardly and forming a seat for the eyelet 12 of the end closure 10. A flexible tube 21 has screw-threaded engagement with the end 18. The tube 16 is also provided with another end 22 which may be fastened to said tube or it may be formed as a part thereof. The end 22 is screw-threaded to engage a screw-threaded actuating member 23 which is provided with a handle 24 at its outer end. The actuating member 23 also embodies therein a circular plate 25 which is rotatably mounted upon the inner end thereof. The plate 25 is depressed at 26 and mounted upon a reduced portion 27 of the member 23, the extremity of which is headed at 28 in a manner to allow the plate 25 to rotate upon the reduced portion 27. The plate 25 is slightly smaller in diameter than the diameter of the slidable end closure 15. The end 22 is also provided with a screw-threaded projection 29 to receive a cap 30.

The operation of the device is as follows:—Assuming the container to be filled with grease, the user inserts the end to which the end closure 10 is attached through the orifice 17 and presses the same against the projection 20 whereupon the frangible material 13 and 14 will be broken as illustrated in Fig. 2. He then moves the other end of the container into the grease gun and advances the screw-threaded actuating member 23 by means of the handle 24 until the plate 25 engages the slidable end closure 15. Further advancing of the screw-threaded

actuating member 23 will cause the slidable end closure 15 to be pushed into the container and thus force the grease through the orifice in the end 18 and through and 5 out of the tube 21. During the operation of the actuating member 23 as soon as the plate 25 contacts with the surface of the end closure 15, the friction between the plate and the closure will prevent said plate 10 from rotating with the actuating member and the latter is thereafter rotated without at the same time rotating the plate therewith, thereby also preventing any tendency to rotate the end closure 15.

15 It will be seen that the plate 25 constitutes not only a means for advancing the slidable end closure 15 in the container, but also performs the function of positioning the tube at one end thereof in the grease gun, while 20 the other end is positioned by the projection 20 of said grease gun.

Referring now to Fig. 4, it will be seen that the general construction and operation of this device is the same as the device hereinbefore described, except that the parts are smaller and are adapted to be detachably fastened to different parts of an automobile in the usual manner. In this embodiment of my invention 5' is the grease container, 6' the grease cup which is provided with a screw-threaded end 18' adapted to be screwed into a portion of an automobile or other machine. 10' is the stationary end closure and 15' is the slidable end closure. 25 23' is the screw-threaded actuating member, 25' the plate on the inner end thereof and 24' the handle on said actuating member. The grease cup 6' differs from the grease

gun 6 in that it is open on opposite sides so that the container 5' can be inserted from either side thereof, thus rendering it possible to insert the container in the grease cup, in places where one side of the grease cup may be rendered inaccessible by adjacent portions of the automobile or other machine to which the grease cup may be fastened.

It is evident that the screw threads may be omitted from the end 22 and from the actuating member 23 mounted therein and said actuating member may slide longitudinally in said end to engage the slidable end closure 15 without departing from the spirit of this invention.

I claim:

1. A grease container having, in combination, a tube, an end closure fast thereto, an eyelet centrally located in said end closure, frangible means sealing said eyelet and another end closure slidable in said tube.

2. A grease container having, in combination, a paper tube, the opposite ends of said tube being turned inwardly and forming interior annular flanges, an end closure fast to one end of said tube and contacting with one of said flanges, an eyelet centrally located in said end closure and an interior end closure positioned to contact with the other of said flanges and slidable within said tube.

In testimony whereof I have hereunto set my hand in presence of two subscribing witnesses.

WARREN B. HOPKINS.
